UNITED STATES PATENT OFFICE

CHARLES O. GUERNSEY, OF PHILADELPHIA, PENNSYLVANIA

COOLING SYSTEM FOR INTERNAL-COMBUSTION ENGINES

Application filed March 4, 1927. Serial No. 172,770.

This invention relates to cooling systems for internal combustion engines used for propelling rail cars.

One of the objects of the invention is to provide an efficient and reliable cooling system for internal combustion engines.

Another object is to provide a cooling system with a variable capacity that is controlled by the engine speed.

10 By this invention means are provided for controlling the circulation of water through an engine cooling system so that positive circulation of the water will be obtained irrespective of the engine speed and greater circulation of the water will be obtained as the speed of the engine is increased.

My invention further consists in the construction, arrangement and combination of various parts of which it is composed as will 20 hereinafter be described and claimed.

In the accompanying drawings:

Figure 1 is a side elevation of the power plant of a rail car showing a cooling system constructed according to my invention;

25 Fig. 2 is an end view of the structure shown by Fig. 1;

Fig. 3 is a plan of the radiator sections;

Fig. 4 is a section taken on the line 4—4 of Fig. 3, and

30 Fig. 5 is a section through a portion of the radiator as seen from the line 5—5 of Fig. 3, showing the detail construction of one of the central tanks.

The roof 5 of the car has suspended therefrom 35 a skeleton hanger 6 carrying a pair of inclined radiator sections 7. The radiator sections are disposed longitudinally of the car and are arranged in V-form immediately below the roof thereof, overlying the power plant, which may be, as diagrammatically shown, an internal combustion engine 8.

The radiator sections are each composed of two interconnected cooling units, mounted in suitable frames 9 that are fixed to the hanger 6.

45 Each of the cooling units is substantially rectangular, and they are so disposed that one corner of each unit will be lower than the rest of the unit.

50 Between each of the cooling units, the

frames 9 are cored to provide a central tank portion 10.

A water storage and expansion tank 11 is carried inside of the engine room of the car. This tank has its highest point below the 55 lowest point of the radiator sections.

The engine 8 has a water circulating pump 12 connected to the bottom of the tank 11 by means of a pipe 13, while the top of the engine is connected to the lowermost corners 60 of the radiator sections by means of a pipe 14 having branches leading to the several sections.

A pipe 15 connects the central portion 10 of each radiator section to the side of the 65 storage tank 11, while connecting the top of each radiator section with the top of the tank 11 is another pipe line 16. Connected to this latter pipe at any suitable point above the tank is a water supply pipe 17, which projects 70 upwardly through the roof of the car.

The lowermost corner of the central portion 10 of each radiator section is provided with a depending flanged opening 18 in which is mounted one end of an angular tube 19. 75

The tube 19 is disposed inside of the central portion 10 and its extremity terminates near the upper end thereof.

Formed in the lower portion of the tube 19 is a relatively small opening 20 providing a 80 restricted outlet passage from the radiator section.

The tube 19 is in communication with the pipe 15 as clearly shown by Fig. 5 and water flowing from the radiator back to the tank 11 85 will pass from the central portion 10 through the opening 20 as well as through the upper open end of the tube 19 into the pipe 15. The amount of water passing through the radiator is limited to the amount which can flow 90 through these passages. However, should the central portion 10 completely fill with water, the surplus liquid will be carried off through pipe 16 which is connected to a vent opening 21 in the top of the radiator section 95 above the open end of the tube 19.

The flow of the water will be returned to the tank 11 as soon as the level of the water in the radiator sections reaches the openings 20 in the tubes 19. As long as the water 100

level in the radiator sections does not extend to the open end of the tube 19 the amount of water returning to the tank 11 is the amount which passes through the opening 20. These openings are as shown, much smaller in diameter than the open ends of the tubes and therefore, when the level of water reaches the upper part of the portion 10 of the radiator sections the return flow will be proportionately increased.

Means for causing a forced circulation of air through the radiator sections includes a fan 22 mounted in an opening 23 in the roof of the car. The fan may be driven by a motor 24.

The roof of the car, on each side of the radiator sections is provided with grilled openings 25.

The fan will draw air through the openings 25, and the radiator sections are so disposed that all of the air delivered by the fan must pass through the cooling units of the radiator. Preferably, these cooling units consist of substantially horizontal tubes 26, which are struck by the air which passes through the spaces between the tubes, as shown by arrows, Fig. 2.

In operation, the tank 11 is filled with water to any desired level, such as that indicated by the letter "L" (Fig. 2). When the engine is started the water is drawn from the tank 11 through the pipe 13, through pump 12 and the engine to the radiator, as indicated by the broken arrows (Figs. 1 and 2). The water enters both ends of the radiators and flows through the tubes 26 to the central tank 10, whence it returns by gravity through the pipes 15 to the tank 11.

The lower outlet passages provided by the openings 20 are calibrated and of sufficient capacity to allow the return of only that amount of water which is pumped at a speed below that necessary to throw the water through the open end of the tube 19.

Thus, when the engine is running at reduced speed, and the pump has reduced capacity, the difference in head between the suction side of the pump and the outlet side is only that from the opening 20 vertically downward to whatever level of water is in the expansion tank 11.

The proportion of the expansion tank may be so established that when the engine is running, the level of the water in the tank will drop below the point indicated by the letter "L" to some point, as indicated by the letter "M".

Therefore, when the engine is idling, the head which must be maintained is only the vertical head from the point indicated by the letter "M" to the openings 20.

When the engine is running at full speed there is no possibility of the flow of the water short circuiting through the lower tubes of the radiator and back to the tank 11, as the

openings 20 are too small to pass any considerable portion of the amount of water which can be pumped at the full speed of the engine.

As the tank 11 is positioned below the lowest point of the radiator, when the engine stops running, the water will drain from the radiator and return to the tank. This feature is very desirable in freezing weather.

It is to be understood that while I have, in the present case, described one embodiment of the invention, I am not limited to the precise structure disclosed, and that other forms of the invention may be utilized without departing from the scope of the appended claims.

I claim:

1. The combination with a car roof having an opening in the top thereof and grilled openings in each side thereof, a fan mounted in said top opening, and a radiator suspended from the roof and having substantially horizontal cooling units disposed in the path of air circulated by said fan from the grilled openings through the top opening.

2. The combination with an internal combustion engine having a water circulating pump, an expansion tank connected to said pump, a radiator disposed above said tank, and connected to said engine and said tank, and means substantially directly responsive to the speed of the engine for increasing or decreasing the volume of the water in said radiator.

3. A cooling system for internal combustion engines including a plurality of radiator sections having water supply inlet and outlet ports, a chamber between said sections and connected thereto and upper and lower passages in said chamber for controlling the flow of water through said sections.

4. The combination with a rail car having an air suction fan mounted in its roof, a skeleton hanger suspended from the roof, a V-shaped radiator carried by said hanger and disposed below said fan, an internal combustion engine below said radiator, a water supply tank between said engine and radiator, means connecting said tank with said radiator and said engine whereby water can circulate therebetween, and means governed by the speed of the engine for circulating water through said radiator.

5. The combination with an internal combustion engine having a water circulating pump, a source of water supply, a radiator overlying said water supply and engine, water connections between said water supply, pump and radiator, and means substantially directly responsive to the speed of the engine for varying the level of water in the said radiator.

6. The combination with an internal combustion engine having a water circulating pump and water supply pipes, an expansion tank having a pipe connected to said engine

6 pump, a radiator disposed above said engine and said tank and having pipe connections therewith, and normally having a water content therein, during the operation of the engine, and means for controlling the volume of water in the radiator.

7. The combination with an internal combustion engine having a water circulating pump and water supply pipe, an expansion 10 tank having a pipe connected to said pump, a radiator disposed above said engine and said tank, pipe connections from said radiator to said tank and from said radiator to said engine, and means for controlling the volume 15 of water flowing through the radiator, said means varying the flow of water through the radiator to increase or decrease the volume of water as the speed of the engine is increased or decreased.

20 8. A cooling system for internal combustion engines including a plurality of radiator sections having a water supply chamber therebetween, means formed in said chamber for controlling the volume of water passing 25 through said radiator sections, and a closed water-circuit between said engine, radiator sections, and water supply chamber.

9. A system for cooling water-cooled internal combustion engines, comprising a 30 low water-cooling unit arranged at an angle to the horizontal, a pipe closing the bottom of said unit and extending short of the top thereof and having a small opening near its bottom, said unit being in a closed water-circuit, said circuit being such that water admitted to the cooling unit in comparatively 35 small quantities while the engine is running slow will discharge into the pipe through the opening, while a comparatively large flow 40 of cooling water in running fast will discharge into the pipe through both its upper end and the opening.
